(57) **CLAIM**

The ornamental design for a light fixture, as shown and described.

DESCRIPTION

FIG. 1 is a top, right, front perspective view of a first embodiment of a light fixture showing my new design;

FIG. 2 is a front view thereof;

FIG. 3 is a top plan view thereof;

FIG. 4 is a right elevational view thereof, the left elevational view being a mirror image thereof;

FIG. 5 is a bottom plan view thereof;

FIG. 6 is a rear view thereof;

FIG. 7 is a top, right, front perspective view of a second embodiment of a light fixture showing my new design;

FIG. 8 is a front view thereof;

FIG. 9 is a top plan view thereof;

FIG. 10 is a right elevational view thereof, the left elevational view being a mirror image thereof;

FIG. 11 is a bottom plan view thereof;

FIG. 12 is a rear view thereof;

FIG. 13 is a top, right, front perspective view of a third embodiment of a light fixture showing my new design;

FIG. 14 is a front view thereof;

FIG. 15 is a top plan view thereof;

FIG. 16 is a right elevational view thereof, the left elevational view being a mirror image thereof;

FIG. 17 is a bottom plan view thereof;

FIG. 18 is a rear view thereof;

FIG. 19 is a top, right, front perspective view of a fourth embodiment of a light fixture showing my new design;

FIG. 20 is a front view thereof;

FIG. 21 is a top plan view thereof;

FIG. 22 is a right elevational view thereof, the left elevational view being a mirror image thereof;

FIG. 23 is a bottom plan view thereof; and,

FIG. 24 is a rear view thereof.

The broken lines shown on the drawings are for illustrative purposes only and form no part of the claimed design.
